ATTORNEYS.

UNITED STATES PATENT OFFICE.

HORACE MONROE, OF SCIPIO, UTAH.

STOVEPIPE FASTENER.

Application filed June 7, 1927. Serial No. 197,138.

This invention relates to holding devices and pertains particularly to a device designed to maintain the upper terminus of a stove pipe chimney in the chimney flue opening.

5 The primary object of the present invention is to provide in a manner as hereinafter set forth, means for gripping a stove pipe and securing the same to a chimney breast in such manner as to prevent the discharge end 10 of the pipe from becoming displaced from a chimney flue opening.

It is well known that the top section of a stove pipe frequently becomes dislodged from a chimney flue opening, either by slowly 15 working therefrom under the effects of vibration or by being knocked accidentally. When this occurs, considerable damage frequently results from smoke and sparks escaping from the pipe into the room in which the stove and 20 pipe is located. The present invention aims to overcome these difficulties by securely attaching the pipe to the chimney wall in the manner hereinafter described.

The present invention aims to overcome the 25 above described difficulties by the provision of a pipe encircling band having attached thereto a locking bar designed to extend through a chimney flue opening and grip the wall of the chimney upon its inner and outer 30 faces thus effectively preventing the removal of the pipe from the flue opening.

Numerous other objects and advantages 35 of the present invention will become apparent as the description of the same proceeds and the invention will be best understood from a consideration of the following detailed description taken in connection with the accompanying drawing with the understanding, however, that the invention is not 40 confined to any strict conformity with the showing of the drawing but may be changed or modified so long as such changes or modifications mark no material departure from the salient features of the invention as ex- 45 pressed in the appended claim.

In the drawing:

Figure 1 shows the upper portion of a stove pipe in side elevation, showing the device embodying the present invention applied thereto and holding the pipe in position in a chimney flue opening.

Figure 2 is a section taken upon the line 2-2 of Figure 1.

Figure 3 is a longitudinal section through 55 the wall engaging portion of the pipe hold-

ing device, disconnected from the encircling band.

Referring now to the drawing in detail, wherein like numerals of reference indicate corresponding parts throughout the several views, the numeral 1 indicates a portion of a chimney wall or breast in section, the section being taken through the flue opening 2 leading into the chimney flue 3. The top and normally horizontal section of a stove pipe is 60 indicated by the numeral 4, the same having one end extended into the chimney flue opening 2 in the usual manner, while the other end is connected to the usual elbow 5, leading to the usual down pipe 6 which terminates 65 at the stove, not shown, as is of course well known.

Surrounding the top pipe section 4, and bearing against the face of the chimney is the usual pipe collar 7 which acts to prevent 70 soot and dirt from working from the chimney flue around the pipe.

The structure embodying the present invention comprises a split collar clamping band 8 which is circumferentially corrugated 80 as is shown to engage the pressed threads 9 of the pipe section. The terminal ends of the split band 8 are turned outwardly in spaced parallel relation as indicated by the numerals 10 and 11, the outturned end 11 having the 85 laterally extending lip 12 formed at the free edge thereof and these ends or ears 10 and 11 are connected together by the bolt 13 carrying the nut 14 which engages the lip 12 and is prevented from turning thereby.

The pipe clamping band is provided at a point diametrically opposite the ears 10 and 11 with a laterally extending curved finger 15 which, when the band is in position about the pipe section 4, is designed to bear against 95 the pipe collar 7 as shown in Figure 1.

Securing the band 8 to the chimney wall 1 is a locking bar indicated as a whole by the numeral 16. This bar is formed in two sections 17 and 18 respectively having the end portions arranged in overlapping relation 100 and riveted together as indicated at 19. The free end of the bar portion 18 is turned back upon itself as indicated at 20 and riveted to the main body portion 18 as indicated at 21 and this back turned portion is then bent at right angles to the main body portion as indicated at 22.

The free end of the portion 17 is also turned back upon itself as indicated at 23 and the 110

body is then turned at right angles as indicated at 24, the angled portions 22 and 24 being arranged upon the same side of the bar 16. The back turned portion 23 of the angled portion 24 is maintained in position by a set screw 25 and projecting from one edge of the back turned portion 23 adjacent the free end thereof, is a plate member 26 provided with a plurality of apertures 27.

- 10 As shown in Figure 1 the bar section 16 is adapted to be extended through the chimney flue opening 2 to position the downturned portion against the inner face of the chimney wall and locate the downturned portion 24 against the outer face of the collar 7, the bar 16 of course extending through the collar as will be readily understood. The plate 26 is positioned between the ears 10 and 11 of the locking band 8 and the bolt 13 which 15 draws these ears together to engage the pipe section 4 is passed through one of the apertures 27 of this plate thus securely fastening the two members together.

From the foregoing, it will be readily un-

derstood that with the locking collar 8 securely engaging the pipe section 4 and the bar 16 engaging the wall 1 and attached to the collar 8, the removal of the pipe section 4 from the chimney flue 2 will be virtually impossible.

Having thus described my invention, what I claim is:

A stove pipe fastener comprising a split collar circumferentially corrugated and having its ends turned outwardly and arranged in spaced relation, a resilient tongue formed on the collar at a point substantially diametrically opposite the ends thereof, a locking bar having downturned inner and outer ends, a plate extending outwardly from the outer downturned end of the locking bar and positioned between the ends of the collar, said plate being provided with a plurality of openings, and a bolt passing through the ends of the collar and through one of the openings of the plate.

In testimony whereof I affix my signature.

HORACE MONROE.
